(57) **CLAIM**

The ornamental design for a faceplate with rocker switch, as shown and described.

DESCRIPTION

FIG. 1 is a perspective view of a first embodiment of my new design.

FIG. 2 is a front elevational view thereof.

FIG. 3 is a rear elevational view thereof.

FIG. 4 is a side elevational view thereof, which is identical when viewed from either side; and,

FIG. 5 is a top plan view thereof.

The broken-line disclosure of the bottom portion of the switch in FIG. 1 is for illustrative purposes only and forms no part of the claimed design, and the bottom of the faceplate is unornamented.
